Primary Examiner — Samantha Wood*Assistant Examiner* — Aula Soroush(74) *Attorney, Agent, or Firm* — Muncy, Geissler, Olds & Lowe, P.C.(57) **CLAIM**

The ornamental design for a respiratory mask, as shown and described.

DESCRIPTION

FIG. 1 is a front elevational view of a respiratory mask showing my new design;

FIG. 2 is a left side view thereof; and,

FIG. 3 is a right side view thereof.

The broken lines illustrate portions of the respiratory mask which form no part of the claimed design.

1 Claim, 3 Drawing Sheets(56)
